UNITED STATES PATENT OFFICE.

GUSTAV O. WILMS, OF MILWAUKEE, WISCONSIN, ASSIGNOR, BY MESNE ASSIGNMENTS, TO THE RELIANCE COMPANY, OF MILWAUKEE, WISCONSIN, A CORPORATION OF WISCONSIN.

PRESSURE RHEOSTAT.

Application filed July 13, 1922. Serial No. 574,803.

This invention relates to a carbon disk rheostat.

The present application is a continuation of application Serial No. 549,352, filed April 5, 1922, as to matter common to both applications.

The prior carbon disk rheostat which is employed in practice has the pressure upon the carbon disks varied in such a way that 10 a quick and steep variation in resistance occurs save in a low narrow range.

In order to obtain a slow and gradual variation in resistance in even a low narrow range many disks are employed and a high 15 pressure is exerted thereon.

The object of the present invention is to provide a carbon disk rheostat in which the resistance has a slow and gradual variation through a wide range.

20 Another object is to provide a carbon disk rheostat in which a high resistance has a slow and gradual variation.

Another object is to provide a carbon disk rheostat in which a few disks are employed.

25 Another object is to provide a carbon disk rheostat which is small, compact and efficient.

Another object is to provide a carbon disk rheostat which may be readily and economically manufactured.

30 Another object is to provide a carbon disk rheostat which will control and regulate radio apparatus, fractional horse-power electric motors, and other electrical appliances which require gradual variation and accurate adjustment in resistance through a wide range.

35 In accordance with the present invention, the carbon disk or other compressible resistor has the pressure thereon regulated and controlled by a low tension spring which has its tension varied by a screw or other actuator.

40 The low tension spring varies a low pressure upon the resistor and has a substantial deflection in varying such pressure from minimum to maximum, and hence, the resistance has a slow and gradual variation through a wide range and the actuator has sufficient movement to be readily operated to obtain definite variation and accurate ad-

55 The accompanying drawings illustrate a rheostat in which the invention is employed, and the views therein are as follows:

Fig. 1 is a side sectional view.

Fig. 2 is a front sectional view on the line 2—2, Fig. 1.

Fig. 3 is a front sectional view on the line 3—3, Fig. 1.

60 Fig. 4 is a view of the actuator parts separated from each other.

Fig. 5 is a curve illustrating the way in which the resistance varies.

65 The rheostat has two carbon disk resistors 1, a low tension spring 2 to control the pressure applied thereto, and a screw actuator 3 to deflect said spring and thereby vary its tension.

70 The resistors are arranged in an insulating casing or holder 4 which has a cover 5 fastened thereto by rivets and provided with lugs 6 for attaching the rheostat to a support.

75 The low tension spring is carried by a guide pin 7 which is movable inwardly through the casing against a spring 8.

80 The actuator has a conical inner end 9 which bears in a conical recess 10 in the guide pin.

85 The casing carries binding terminals 11 through which the resistors are connected in circuit, and these terminals have switch contacts 12 for short-circuiting and removing the resistors from circuit after the resistance has been reduced to a minimum.

90 The actuator is threaded in a bushing carried by the cover and it is provided with a knob 13 for turning the same to operate the rheostat.

95 The low tension spring in its initial position is disengaged from the resistors and opens the circuit through the resistors.

When the rheostat is in operation, the resistance is varied by turning the actuator to deflect the low tension spring and vary its tension and thereby vary the pressure upon the resistors.

100 The circuit through the resistors extends from the terminals 11 through the resistors 1 and across the low tension spring 2.

When the actuator has been advanced to reduce the resistance to the minimum, the guide pin 7 engages the switch contacts 12

and thereby connects the terminals 11 to short-circuit the resistors and remove the same from circuit.

The low tension spring merely varies a low pressure upon the resistors and has a substantial deflection to vary such pressure from minimum to maximum.

Accordingly, the resistance has a slow and gradual variation through a wide range and the actuator is allowed sufficient movement to enable it to be readily operated to obtain definite variation and accurate adjustment in resistance.

The resistance, due to having a slow and gradual variation through a wide range has a substantial uniform variation through a wide working range.

The curve Fig. 5 illustrates the relation between the resistance variation and the actuator movement.

The ordinate represents resistance variation and the abscissa actuator movement.

The resistance has a slow and gradual variation through a range between about one (1) ohm and twenty-five (25) ohms, and the actuator has about two turns in varying the resistance through that range.

The spring and not the disks controls and determines the range through which the resistance has a gradual variation, and hence, few disks may be employed and the rheostat as a whole may be small and compact.

The low tension spring is proportioned to obtain gradual variation in resistance through the range that is required for the service in which the rheostat is to be employed.

The invention set forth herein provides a rheostat in which the resistance may be regulated and adjusted through a sufficient range to regulate and control radio apparatus, small fractional horse-power motors and other electrical appliances which require definite variation and accurate adjustment in resistance through a wide working range.

Of course, different rheostats which incorporate the invention may be devised, and such rheostats may be employed for different purposes.

The invention claimed is:

1. A rheostat comprising a carbon disk resistor, a low tension spring controlling a low pressure upon said resistor and proportioned to cause a gradually and substantially uniform variation in resistance through a wide working range, and an adjustable actuator to operate said spring.

2. A rheostat comprising a carbon disk resistor, a low tension spring controlling a low pressure upon said resistor and proportioned to cause a gradually and substantially uniform variation in resistance through a wide working range, and a screw actuator to operate said spring. 60

3. A rheostat comprising two carbon disk resistors, low tension springs controlling a low pressure upon said resistors and proportioned to cause a gradually and substantially uniform variation in resistance through a wide working range, and an adjustable actuator to operate said springs. 65

4. A rheostat, comprising in combination, compressible resistors, composed of contacting electrodes, a contact spring for varying the compression of said resistors and electrically connecting the same, means for varying the tension of said spring, and a spring for removing said contact spring from engagement with said resistors. 75

5. A rheostat, comprising in combination, two compressible resistors each having contacting electrodes, an actuator for controlling the compression of said resistors, and resilient means arranged between said actuator and said resistors for electrically connecting said resistors and having the tension thereof varied by said actuator. 80

6. A rheostat, comprising in combination, a holder, a fine pitch screw, a compressible resistor arranged between said holder and said screw, a spring arranged between said resistor and said screw for varying the compression of said resistor and having its tension varied by said screw, and means controlled by said screw for removing said resistor from circuit. 85

7. A rheostat, comprising in combination, a holder, a fine pitch screw, two compressible resistors arranged between said holder and said screw, resilient means interposed between said resistors and said screw and electrically connecting said resistors, and means controlled by said screw for removing said resistors from circuit. 95

8. A rheostat, comprising in combination, a casing, two compressible resistors arranged therein, an electrical terminal for each resistor carried by said casing, a spring for compressing said resistors and electrically connecting the same, and a fine pitch screw 100 for varying the tension of said spring. 105

In witness whereof, I have hereunto subscribed my name.

GUSTAV O. WILMS.
